UNITED STATES PATENT OFFICE

AUGUST F. OSTERLIND, OF ST. PAUL, MINNESOTA; FRANK H. OSTERLIND AND JOHN A. JACOBSON, ADMINISTRATORS OF SAID AUGUST F. OSTERLIND, DECEASED

METHOD OF MAKING CALENDARS

Application filed July 28, 1927, Serial No. 209,010. Renewed September 12, 1929.

It is the present general practice in the printing and binding of calendars to print the several units, such as the months of the year, upon separate sheets and then to manually gather the sheets into groups, each of which, contains the sheets required to make up a complete calendar pad and then to bind the sheets of each pad together.

With this method, a large part of the cost 10 of the calendar is represented by the item of labor required for the gathering of the leaves together preparatory to binding.

It is my object to reduce the cost of manufacturing calendars by eliminating the hand 15 work heretofore required in gathering of the printed sheets into groups.

In the method of this invention, I print all 20 of the units or calendar months for each calendar on a single integral sheet. The several units are arranged into two groups, one group being printed on one side of the sheet and the other on the opposite side, leaving blank spaces upon the proportions of the sheet located directly back of each unit or month. 25 Subsequently, the sheet so printed is folded in a suitable machine or otherwise to form a calendar pad and finally the margins of the pad are trimmed to free the individual units or leaves and the leaves are bound in any suitable or well known manner. In the following 30 specification, I have described an arrangement of the units on a sheet, which is adapted for use with a folding machine of common type.

35 The invention will be best understood by reference to the accompanying drawings in which Figure 1 is a diagrammatic plan view showing a suitable arrangement of the several units constituting a calendar pad upon 40 a single sheet; Figs. 2, 3, 4 and 5 illustrate the same sheet after the first, second, third and fourth folds respectively, Fig. 5 showing the sheet ready for trimming and Fig. 6 shows diagrammatically a suitable layout of a unit 45 whereby a plurality of calendars of different sizes and shapes may be prepared in a single folding operation by following my improved method.

In carrying out my invention, two printing 50 presses may be employed, the type neces-

sary for printing one-half the units of the calendar being set up on one press and the other half upon the other press. Thus, where a pad of the common type having a leaf for each month is to be manufactured, the monthly units representing six months may be arranged for printing, as indicated in full lines in Fig. 1 upon one press and the units for the other six months of the year may be set up on the other press. The units indicated in full lines in Fig. 1 are printed on one side of the sheet and the units indicated in dotted lines are printed on the reverse side by passing the sheet through the other press. It will be noted that portions of the sheet directly 55 back of each unit are left blank. In other words, the several units upon one side of the sheet are spaced apart and the units printed upon the opposite side of the sheet register with the spaces on the reverse side.

Now the printed sheet may be passed through a folding machine to produce a pad, as indicated in Fig. 5, having a superficial area approximately equal to the size of one of the units. With the arrangement shown 70 in Fig. 1, the first fold is along a vertical line, indicated by the numeral 7 and extending across the sheet. This produces a sheet like that shown in Fig. 2. The second fold is along a horizontal, dotted line 8, shown 75 in Figs. 1 and 2, and results in reducing the sheet to the form shown in Fig. 3. The third fold is along a vertical line 9 and the fourth along the horizontal line 10 to successively 80 produce the forms shown in Figs. 4 and 5. 85 The several units are now disposed in proper sequence, one upon another, and a pad having a superficial area the size of one of the units results. This pad is now trimmed along the lower left and right edges to separate 90 it into leaves, each leaf bearing the printed representation of a month or other unit. Finally, the pad is bound in any suitable or well known manner and the calendar is complete.

95 Similar procedure may be followed to print two calendars by the use of a single press. Thus, type or plates for printing the several units of a complete calendar may be set up on one press with the units in spaced 100

relation, as indicated in Fig. 1, and then one side of the sheet is printed. The sheet is now reversed and a complete calendar printed upon the other side upon the portions of the sheet which register with the spaces between the first printed units. The sheet so printed is then cut into halves, each similar to that shown in Fig. 1. The subsequent procedure in folding, trimming and binding is like that above described.

10 Where it is desired to print a plurality of calendars of different sizes and shapes, each unit of a printed sheet divided like that above described, may be arranged to constitute the corresponding unit of a plurality of calendars and in such case each unit may be divided, as indicated in Fig. 6. After printing and folding of the sheets having units like that indicated in Fig. 6, the folded pad 15 may be cut into a plurality of calendars by cutting along the lines 11, 12 and 13.

Obviously, where the sheet is to be folded differently from that described, a different arrangement of the units is required in order 20 to avoid rearrangement of the leaves after folding.

It will be understood that where the term "unit" is used in the following claims, it is intended to include any suitable division of 25 the calendar year, such as the month, or a shorter period, or a plurality of months, which may be desired upon a leaf of the calendar.

Claims:

30 1. The method of making calendars which consists in printing upon an integral sheet a plurality of units arranged in two groups, the units of one group being disposed in spaced relation to each other and the units 35 of the other group being printed on the reverse side of the sheet and in registry with the spaces between units of the first group, subsequently folding the sheet successively and alternately along vertical and horizontal 40 lines to form a pad having a superficial area approximately equal to the size of one unit and in which the units are disposed in proper sequence and then separating at least some 45 of the edges of the units to form the leaves of a pad.

50 2. The method of making calendars which consists in printing upon an integral sheet a plurality of units arranged in two groups, the units of one group being printed upon 55 one side of the sheet and the units of the other group being printed on the reverse side of the sheet, subsequently folding the sheet along alternate vertical and horizontal lines to 60 form a pad and in which the units are disposed in predetermined order and then separating at least some of the folded edges to form the leaves of a pad.

65 3. The method of making calendars which consists in simultaneously printing upon one side of an integral sheet all of the units re-

quired to make a calendar, the units being disposed in spaced relation to each other, then printing upon the reverse side of said sheet a similar group of units, the units of the second group being printed in registry with the spaces between units of the first group, then cutting said sheet to form two calendar sheets, subsequently folding each of said sheets twice horizontally and twice vertically to form pads, each having a superficial area approximately equal to the size of one unit and then separating at least some of the edges of the units to form the leaves of two calendar pads.

In testimony whereof, I have hereunto 80 signed my name to this application.

AUGUST F. OSTERLIND.
